[57] CLAIM

The ornamental design for a wine rack, as shown.

DESCRIPTION

FIG. 1 is a front perspective view, to a slightly reduced scale, of a wine rack, showing my new design;
FIG. 2 is a side elevational view, the opposite side being a mirror image thereof;

FIG. 3 is a front elevational view;

FIG. 4 is a rear elevational view;

FIG. 5 is a top plan view; and,

FIG. 6 is a bottom plan view.
